UNITED STATES PATENT OFFICE.

FRANK K. LATHROP, OF DAYTON, OHIO, ASSIGNOR TO THE OHIO RAKE COMPANY, OF DAYTON, OHIO, A CORPORATION OF OHIO.

DISK HARROW.

1,073,488.

Specification of Letters Patent. Patented Sept. 16, 1913.

Application filed May 6, 1912. Serial No. 885,427.

To all whom it may concern:

Be it known that I, FRANK K. LATHROP, a citizen of the United States, and a resident of the city of Dayton, in the county of 5 Montgomery and State of Ohio, have invented certain new and useful Improvements in Disk Harrows, of which the following is a full, clear, and exact description, reference being had to the accompanying 10 drawings, forming a part of this specification.

My invention relates to improvements in disk harrows provided with two sets or gangs of rotary disks or cutters arranged 15 one in front of the other, and in which the round or cut disks of each gang are usually turned in opposite directions so that the rear set will level off and thoroughly pulverize the ground thrown up by the forward 20 set and the ground thus effectively treated in one operation.

Hitherto in such constructions the frames carrying the two gangs of disks have either been rigidly connected together to 25 form a single rigid frame or the frames for the two gangs have been separate and merely coupled together in tandem by a central coupling bar.

In the former case the rigidity of the 30 single frame presents difficulties in turning corners, while in the latter difficulty is experienced in keeping the two sets of gangs in line while traversing the field.

In a prior application, Serial No. 570,664, 35 duly allowed February 23, 1912, I have devised a construction to obviate these difficulties in which the main frame to which the gang frames are swiveled, is formed with flexible side bars which, while maintaining sufficient rigidity for the purpose, 40 permit the main frame to flex laterally under side strains in turning corners.

The object of my present invention is to provide rigid side bars for the main 45 frame pivoted to the front and rear bars of the frame, to permit the frame to swing laterally, and in which the rigidity of the frame is maintained by springs exerting their influence between the side and trans- 50 verse bars of the main framework.

In the drawings, Figure 1 is a top plan

view of my improved construction. Fig. 2 is a central longitudinal section of the same.

The main frame is made up of a pair of parallel angle bars 1, 2, properly bolted together to form the front bar of the frame, side angle bars 3, 4, which are loosely pivoted to swing horizontally on vertical bolts 5, 6, to plates 7, 8, bolted to the front bar. The rear ends of these side angle bars 3, 4, 60 are in turn pivoted to swing horizontally by bolts 9, 10, to the flattened ends of the rear cross bar 11. In this way, a main frame of rigid members is provided, adapted to swing laterally on vertical pivots at the four 65 corners of the frame. The front pivotal connection on the bolts 5, 6, is made sufficiently loose to allow vertical play for the rear portion of the frame.

The necessary rigidity for the main frame 70 is obtained by the use of the coiled springs 12, 13, which are coupled between the side bars 3, 4, respectively, and the rear bar 11, and extend diagonally across the inside of the rear portion of the frame. These 75 springs are sufficiently powerful to maintain the proper alignment of the gangs and to preserve the rectangular structure of the frame under the travel of the implement in a straight line, but under side strains 80 permit the frame to swing laterally.

Securely bolted to the front cross bar at the middle and braced by the side braces 14, 14, is the tongue 15 of the harrow. Upon each side of this tongue is pivotally mounted a hand lever 16, 17, provided with the usual notched segments 18 and the hand latches 19, for locking the levers and the disk gangs in any desired angular position to the line of draft. 90

The disk gangs are arranged in two sets, two gangs A, B, in front and two gangs C, D, in the rear, one gang of each set on one side of the line of draft, and the other gang on the other side of the line of 95 draft, and with the disks or cutters turned in opposite directions so that the rear gangs will throw the dirt in a direction opposite to the throw of the front gangs.

The disks 20 of each gang are strung together on a gang shaft 21, with spools or sleeves 22 to separate the disks, the gang

shaft having a head 23 at one end and being screwthreaded at the other with the disks and sleeves drawn together and held by a nut 24.

5 Each of the front gangs is secured by hangers or straps 25 to a separate gang frame 26 in the usual way and each of these gang frames is suspended and supported from the main frame by a coupling 27 and 10 horizontal bolt so that each gang will swing in a horizontal plane. The inner ends of each of these two front gangs are separately connected by the connecting bars 28 to the lower ends of their respective adjusting levers 16, 17, whereby upon shifting the lever the proper angle to the line of draft may be given to the gang in the usual way. Each of the rear gangs is also mounted in a 15 separate gang frame made up of two parallel bars 29, 29, and each gang is supported from its gang frame by hangers 30 in which the gang shaft is properly journaled.

The gang frames 29 are pivotally secured 25 to the main frame to swing in a horizontal plane about midway of their length by the same bolts 9, 10, which pivotally connect together the rear cross bar 11 with the side bars 3, 4, and the inner ends of these two gangs are held in a horizontal plane and 30 adapted to be adjusted angularly to the line of draft by the coupling blocks 31, 31.

One coupling block is provided for each gang and it consists of a rectangular loop 35 and an opening 32 of a height to loosely embrace the transverse cross bar 11 of the main frame and to allow free movement back and forth of the loop on the cross bar. Each loop is also pivotally secured to the inner 40 end of its respective gang frame by the pivot pin 33. Each loop 31 is connected by its connecting bar 34 to its respective adjusting lever 16, 17, so that the gangs may be properly adjusted at the desired angle to 45 the line of draft for the varying conditions of soil and these connecting bars are preferably made in sections coupled together at 50 35. As the disks of the front gang are set in opposite directions to the disks of the rear gang, the desired angular adjustment of the front and rear gangs will be in opposite directions so that the connecting bars 34 for the rear gangs are pivotally mounted to the levers 16, 17, above the pivots of the levers 55 to the tongue and the connecting bars 28 for the front gangs are mounted at the lower ends of these levers below the tongue pivots.

It will be evident that when it is desired 60 to use the front harrow alone, the rear harrow can be readily and easily removed by disconnecting the side bars 3, 4, in front and separating the connecting bars 34.

While I have illustrated the harrow as

provided with round disks, the ordinary cut disks are also provided, and for many 65 varieties of soil the cut disks are preferable, owing to their spading action.

The usual driver's seat 36 is provided, supported by a standard 37 bolted on the rear end of the block 38, secured on the 70 tongue.

Having thus described my invention, what I claim as new and desire to secure by Letters Patent, is:

1. In a disk harrow, the combination with 75 front and rear gang frames, of a main frame, to which the gang frames are pivotally secured, said main frame comprising a front and a rear transverse bar, with side bars adapted to swing in a horizontal plane, 80 with means for holding the main frame normally rigid, whereby the main frame will swing laterally under side strains in turning corners without affecting the rigidity of the main frame during the forward progress of the machine. 85

2. In a disk harrow, the combination with front and rear gang frames, of a main frame, to which the gang frames are pivotally secured, said main frame comprising 90 a front and a rear transverse bar, with rigid side bars pivoted to the front bar to swing in a horizontal plane, with means for holding the main frame normally rigid, whereby the main frame will swing laterally 95 under side strains in turning corners without affecting the rigidity of the main frame during the forward progress of the machine.

3. In a disk harrow, the combination with front and rear gang frames, of a main harrow, to which the gang frames are pivotally secured, said main frame comprising a front and a rear transverse bar with rigid side bars adapted to swing in a horizontal plane, and springs intermediate the rear portion of 100 the side bars and the rear cross bar, whereby the main frame will swing laterally under side strains in turning corners and at the same time the rigidity of the main frame during the forward progress of the machine 110 will be maintained.

4. In a disk harrow, the combination with front and rear gang frames, of a main frame, to which the gang frames are pivotally secured, said main frame comprising a 115 front and a rear transverse bar, with rigid side bars adapted to swing in a horizontal plane, loops mounted loosely on the rear cross bar and pivotal connection for said loops, with the inner ends of said rear gang 120 frames, with adjusting levers and connecting bars to said loops whereby the rear gang frames will be held in horizontal position and at the same time angularly adjusted.

5. In a disk harrow, the combination

with front and rear gang frames, of a main frame to which the gang frames are pivotally secured, said main frame comprising a framework of individual rigid members consisting of side bars, and front and rear cross bars pivotally secured together at the corners to swing laterally, with springs to

maintain the rigidity of the frame under normal conditions.

FRANK K. LATHROP.
